United States Patent Office

Des. 212,557
Patented Oct. 29, 1968

212,557

GUITAR OR SIMILAR ARTICLE

Cecil A. Null, P.O. Box 23, and George L. Lewis, 732
Cheyrl Ave., both of Madison, Tenn. 37115

Filed Sept. 22, 1967, Ser. No. 8,694

Term of patent 14 years

(Cl. D56—1)

FIG. 4.

FIG. 1.

FIG. 2.

FIG. 3.

FIG. 5.

FIG. 6.

FIG. 1 is a side elevational view of a guitar or similar article, showing our new design;

FIG. 2 is a top plan view;

FIG. 3 is an opposite side elevational view;

FIG. 4 is a front end elevational view;

FIG. 5 is a rear end elevational view; and

FIG. 6 is a bottom plan view thereof.

The dominant features of our new design are shown in solid lines in the drawing.

We claim:

The ornamental design for a guitar or similar article, as shown and described.
